UNITED STATES PATENT OFFICE.

ROBERT GARLAND POOLE, OF BALTIMORE, MARYLAND.

STATION-INDICATOR.

1,358,873.

Specification of Letters Patent. Patented Nov. 16, 1920.

Application filed February 17, 1920. Serial No. 359,330.

To all whom it may concern:

Be it known that I, ROBERT GARLAND POOLE, a citizen of the United States, residing at Baltimore, in the county of Baltimore 5 and State of Maryland, have invented new and useful Improvements in Station-Indicators, of which the following is a specification.

The object of my present invention is the 10 provision of a simple and reliable electro-mechanical station indicator, and one well adapted to withstand the vibrations and the usage to which station indicators are ordinarily subjected on cars.

15 To the attainment of the foregoing, the invention consists in the improvement as hereinafter described and definitely claimed.

In the accompanying drawings, hereby made a part hereof:

20 Figure 1 is a longitudinal vertical section of my novel station indicator.

Fig. 2 is a front elevation of the same.

Figs. 3 and 4 are enlarged detail views 25 to the roller for moving step by step the endless band that bears the name of the station.

Similar numerals of reference designate 30 corresponding parts in all of the views of the drawings.

The casing 1 of the improved station indicator is provided in its forward end wall 2 with a window 3 for the display of the names of the stations on an endless band 4, 35 of appropriate translucent material.

Carried at the inner side of the wall 2 and disposed above and below the horizontal center of the window 3 are guide rollers 5 between which and the window a vertical 40 stretch of the band 4 is movably disposed, as indicated by 6.

In rear of the said stretch 6 is arranged in the casing an incandescent electric lamp 7, the filament of which is designed to be 45 electrically connected with a source of electrical energy (not illustrated). While I prefer to employ an electric lamp for obvious reasons, it is manifestly within the purview of my invention to employ a lamp of 50 any other description.

Disposed in fixed relation in the casing 1 in rear of the lamp 7 is an inclined rack 8, the upper end of which is considerably in advance of the lower end thereof, for a reason 55 that will be hereinafter made clear. In

said rack 8 are mounted in spaced relation a plurality of transverse rollers 9.

Adjacent to the rear of the casing 1 is arranged therein a rack 10 that carries a vertical series of spaced transverse rollers 60 11. The upper end of the said rack 10 is hinged at 12 to the top wall of the casing, and the lower portion of the rack is subject to the action of a tensioning screw 13, mounted at 14. Any desired number of the 65 screws 13 may be employed as found expedient.

Trained over the rollers 5 and the rollers 9 and 11 in the manner clearly shown in Fig. 1 is the before mentioned endless band 70 4, and therefore it will be apparent that when the lowermost of the rollers 9 is turned clockwise about its axis, the band 4 will be moved in the direction indicated by arrow in Fig. 1, so as to present the station names 75 thereon one after the other in interposed relation between the window 3 and the lamp 7, with the result that the said names will be prominently displayed to the passengers in a car.

In order to enable a conductor or other person in authority to turn the said lowermost roller 9 and thereby move the band 4 step by step at intervals, and this while such person is at a considerable distance 85 from the indicator, I provide the electro-mechanical means shown in Fig. 1. The said means comprises an electro-magnet 15. This magnet is designed to be arranged in a normally open circuit with a source of 90 electric energy and a switch (not shown) which latter may be and preferably is in the form of a push-button located adjacent to a conductor's stand adjacent to the rear end of a car. The said means also comprises a rectilinearly movable armature 16 complementary to the magnet 15 and carried at the forward end of a rack bar 17, guided in standards 18, and subject to the action of a retractile spring 18^a for 100 moving it rearwardly when the magnet 15 is deenergized. The rearward movement of the bar 17 is limited by a stop-collar Fig. 1, arranged to coöperate with the foremost standard 18. Loose on the shaft of the low- 105 ermost roller 9 is a spur gear 19 that is intermeshed with the rack bar 17 and is provided at 20 with a resilient dog. The said dog 20 is opposed, Fig. 4, to a ratchet 21, fast on the shaft of the lowermost roller 9. 110

From this it follows that incidental to forward movement of the rack bar 17, the lower roller 9 will be turned clockwise to feed the band 4 in the direction indicated, and that on the rearward movement of the bar 17, the dog 20 will "click" idly over the teeth of the ratchet 21, so that no turning movement of the said roller 9 will attend the rearward movement of the bar 17.

- 10 It will be apparent from the foregoing that when one station name is displayed through the window 3, all that is necessary to be done in order to bring about the display of the next station is for the conductor to close the switch and energize the magnet 15. Then when the conductor opens the switch, the parts will be restored to the positions shown in Fig. 1, ready for the succeeding operation.
- 15 It will also be apparent that the arrangement of the forward rollers 9 in an inclined series as illustrated, affords ample space in the lower forward portion of the casing 1 for the positioning and operation of the electro-mechanical actuating mechanism of the indicator.
- 20
- 25

Having described my invention, what I claim and desire to secure by Letters-Patent, is:

A station indicator comprising a casing 30 having a window in one of its end walls, guides carried by said wall in rear of said window, a rear rack hinged at one end in the casing, adjustable means acting against the opposite end of the rack to hold said 35 rack against forward movement, transverse rollers mounted in said rack, a forward, downwardly and rearwardly inclined rack fixed between the top and bottom walls of the casing, transverse rollers in said rack, a 40 translucent endless band trained over the rear and forward rollers and through the guides, a lamp in the casing and in rear of the forward stretch of the band and in the space afforded between said stretch and the 45 forward rack, and electro-mechanical and spring means in the lower portion of said space and connected with the lowermost forward roller to move the endless band step by step.

In testimony whereof I affix my signature.
ROBERT GARLAND POOLE.
